Primary Examiner—Bernard Ansher*Assistant Examiner*—Lucy Lieberman*Attorney, Agent, or Firm*—Burd, Bartz & Gutenkauf[57] **CLAIM**

The ornamental design for a top portion of a bottle, as shown and described.

DESCRIPTION

FIG. 1 is a perspective view of a top portion of a bottle showing our new design;
 FIG. 2 is a front elevational view thereof;
 FIG. 3 is a rear elevational view thereof;
 FIG. 4 is a side elevational view thereof, the opposite side being a mirror image thereof;
 FIG. 5 is a top view thereof;
 FIG. 6 is a perspective view of a modified form of the top portion of a bottom;
 FIG. 7 is a front elevational view of FIG. 6;
 FIG. 8 is a rear elevational view of FIG. 6;
 FIG. 9 is a side elevational view of FIG. 6, the opposite side being a mirror image thereof; and,
 FIG. 10 is a top view of FIG. 6.
 The broken lines showing the body portion of a bottle are for illustrative purposes only and do not form part of the claimed design.
